UNITED STATES PATENT OFFICE

ROBERT G. WILSON, OF WAYNE, AND RONALD M. WILSON, OF UPPER DARBY, PENNSYLVANIA, ASSIGNORS TO THE HUFFMAN MANUFACTURING COMPANY, OF DAYTON, OHIO, A CORPORATION OF OHIO

LIQUID MEASURING AND DISPENSING CAN

Application filed June 13, 1929. Serial No. 370,600.

This invention relates to a liquid measuring and dispensing can, and has particular reference to a can which is provided with a port in the bottom of the same communicating with a flexible tube for draining the can while retaining the can in an upright position and a hand operated valve for controlling the port.

In cans of the type just above described where there is provided means for retaining the port open, the delivery tube is sometimes returned to its upright position and the can refilled with the valve open. This results in filling the tube to the same level as the can is filled, thereby giving an excess amount of liquid, and when the tube is lowered to dispense the liquid, it is usually splashed over the outer surface of the article or thing into which the liquid is to be delivered.

The object of this invention is to provide a measuring and dispensing can in which the tube cannot be hooked or held in its upright position until the valve is lowered for closing the delivery port.

A further object of the invention is to provide means for insuring the proper amount of liquid being placed in the can.

Still another object of the invention is to provide means for accomplishing the above objects and which can be economically manufactured and applied to existing dispensing cans as well as to cans in the process of manufacture.

The drawing illustrates an embodiment of the invention and the views therein are as follows:—

Figure 1 is a vertical sectional view of a measuring and dispensing can embodying the invention,

Figure 2 is a top plan view with a portion broken away,

Figure 3 is a fragmentary sectional view taken on the line 3—3 of Figure 1 and looking in the direction of the arrows,

Figure 4 is a fragmentary view of the manner in which the flexible rod is hooked in upright position in the conventional measuring and dispensing can.

According to the invention a dispensing can which has a port or outlet in the lower

portion thereof controlled by a valve which is actuated by a suitable operating device and which port communicates with a delivery tube or spout which can be tilted from its discharge position to an upright position, is 55 provided with a device to retain said tube or spout in an upright position and which comprises a movable member which is so arranged with relation to the valve operating device that when said operating device is in the position which it normally occupies when the valve is open said movable member will be retained in a position to prevent the spout or tube from being operatively engaged by said retaining device, said movable member being 60 movable to a position to permit said retaining device to operatively engage said tube or spout only when said operating device is moved to a position to close said valve. In the present drawings we have illustrated one 65 embodiment of the invention in which the retaining device comprises a single member having at its outer end a hook-shaped portion to engage the spout and which is connected with the valve operating device for 70 movement thereby into and out of a position in which the spout cannot be operatively engaged by the hook shaped portion thereof. It will be understood, however, that this particular embodiment has been chosen for the 75 purpose of illustration only and that the retaining device may take various forms and the movable part thereof may be associated with the valve operating device in various ways.

In that embodiment of the invention here illustrated the can body 6 is provided with a bottom 7 having a port 8 therein and which said port is adapted to receive an elbow 9 while a flexible tube or spout 11 is connected 80 to the outer end of the elbow and is provided on its outer end with a nozzle 12.

The port is controlled by a valve 13 which is carried by an arm 14 pivotally mounted at 16 in the support 17. The arm is provided 85 with an upright portion 18 for receiving a valve operating rod 19 which extends through the top of the can and is provided at its upper end with a thumb piece 21. The arm 14 is prevented from lateral movement by 100

means of a bifurcated guide 22 fastened to the bottom 7 of the can.

The rod 19 extends through slots 23 in the guide member 24 and this guide member is arranged to house a spiral spring 26 between the wall of the can and the rod, while the slots 23 are provided with recesses 27 located at points near to the wall of the can so that when the rod 19 is pulled backward through the slots 23, it may be pressed to the side and retained in such position so as to hold the valve 13 in raised position and the port 8 open.

So far the mechanism which has been described is conventional and by reference to Figure 4, it will be seen that the nozzle 12 on the end of the flexible delivery tube is provided with a hook 28 which, when said tube is not in use, is adapted to engage the upper edge of the can to maintain the same in an upright position.

With a structure such as described and with a hooked member such as shown in Figure 4, it often happens that the valve operating rod 19 is retained in one or the other of the recesses 27 when the contents of the can have been drained and the flexible member is moved to its upright position and hooked in such position by means of the hook 28.

In such an event, when the can is refilled with liquid, the liquid will flow into the tube and to a level on the same plane as the level to which the can is filled, thereby providing an excess amount of the liquid and utterly destroying the utility of the can as a measure.

In the use of the can it is usually held by the handle 29 and maintained in its upright position, and in case the can has been filled with the valve open, and the flexible tube 11 thus also filled, the movement of the tube or spout to its lowered position, for delivery into a crank case or other receptacle, will permit the liquid to be discharged therefrom as soon as the outer end of the tube passes below the upper level of the liquid in the can proper, thereby causing a splashing or spilling of the liquid before the end of the nozzle has been inserted in the crank case or is otherwise in proper position for the delivery of the contents of the can.

To overcome this objection we have provided a spout retaining device which, in the form here illustrated, comprises a rod 31 which is connected in any suitable manner at its inner end to the valve operating rod 19. This rod passes out through an opening 32 located at any convenient place in the body of the can and it is provided on its outer end with a hooked member 33 whose contour is substantially the same as the nozzle of the delivery tube, and when the parts are in the position to close the valve, such as shown in Figure 1, there is just sufficient clearance between the end of the hook, designated by the numeral 34, and the side of the can, as designated by the numeral 35, (see

Figure 2) to permit the nozzle of the flexible tube to pass therebetween and fall into hooked relation with the hooked member 33.

When, however, the valve rod 19 is retracted, as shown by the dotted lines in Figure 1, so that the valve 13 is raised and the port 8 open, as also shown by dotted lines in Figure 1, the end of the hook 34 will be drawn toward the body of the can or toward the point 35, as shown by the dotted lines at 34' in Figure 1, so that the space between these two points is insufficient to permit the nozzle 12 to pass therebetween.

A slight jar of the nozzle 12 against the hooked member will ordinarily disconnect the operating rod 19 from its position in the recess 24, but in any event, the one handling the can will at once be apprised of the fact that the valve is open and will immediately close the same by disengaging the rod 19 from the recess 27 so as to hook the upper end of the flexible rod 11 or the nozzle 12 in the hooked member 33.

The measuring and dispensing can shown in the drawing is merely for the purpose of illustrating the invention and it is to be understood that various types of cans may be used and various modifications and changes may be made without departing from the invention herein set forth and hereafter claimed.

The invention is hereby claimed as follows:

1. In a liquid dispensing can provided with a flexible tube communicating with a port in the bottom of the can and a valve normally closing the port and opened by operating means at the top of the can, movable means connected with said operating means for holding said tube in an upright position and available only when said valve is closed.

2. In a liquid dispensing can provided with a flexible tube communicating with a port in the bottom of the can and a valve normally closing the port and adapted to be opened by drawing an operating rod to the rear, movable means connected with said operating rod for holding said tube in an upright position and available only when said operating rod is in its forward position and the valve closed.

3. In a liquid dispensing can provided with a flexible dispensing tube communicating with a port in the bottom of the can, a valve for said port, an operating rod for said valve, means for holding said rod in a position to maintain the valve open, and means comprising a rod fastened to said operating rod and having a hook for maintaining said tube in upright position, said hook being retracted so as to be non-available for the holding of said tube when said operating rod is holding the valve open.

4. In a liquid dispensing can having a tilt-

- able discharge spout leading from the lower portion thereof, a valve to control the discharge of liquid through said spout, and a device for operating said valve, a device to retain said spout in an upright position comprising a movable part which, when in one position, will prevent said spout from being operatively engaged by said retaining device, said valve operating device being so arranged with relation to said retaining device as to prevent the movement of said part from said position while said operating device is in the position it normally occupies when said valve is open.
5. In a liquid dispensing can having a tilt-able discharge spout leading from the lower portion thereof, a valve to control the discharge of liquid through said spout, and means for operating said valve, a device to retain said spout in an upright position, said retaining device being connected with said valve operating means and having a spout engaging portion so arranged that the spout can be operatively engaged therewith only when said valve operating means is in a position to close the valve.
6. In a liquid dispensing can having a tilt-able discharge spout leading from the lower portion thereof, a valve to control the discharge of liquid through said spout, and means for operating said valve, a spout retaining device connected with and movable by said valve operating means and having a hook-shaped portion extending outwardly from that side of said can adjacent to said spout and so arranged that said spout can be inserted therein only when said valve operating means is in a position to close the valve.
7. In a liquid dispensing can having a tilt-able discharge spout leading from the lower portion thereof, a valve to control the discharge of liquid through said spout, and means mounted within said can for operating said valve, a device to retain said spout in an upright position comprising a movable member having a spout engaging portion arranged exteriorly of said can and having a part extending into said can and so arranged with relation to said valve operating means that when the latter is in a position to open said valve said movable member will be retained in a position in which it cannot be operatively engaged by said spout.
8. In a liquid dispensing can comprising a receptacle, a tilttable spout leading from the lower portion of said receptacle, a valve to control the discharge of liquid through said spout, and a valve operating device, means controlled by the position of said valve operating device to retain said spout in an upright position, said means being operable to so retain said spout only where said valve is closed.
9. In a liquid dispensing can provided with a tilttable discharge spout leading from the lower portion thereof, and a valve to normally prevent the discharge of liquid through said spout, means for holding said spout in an upright position comprising a part movable into and out of a position to render said holding means inoperative, and means connected with said valve to control the position of the movable part of said holding means.
10. In a liquid measuring and dispensing can provided with a tilttable dispensing spout communicating with the lower portion of said can, and a valve to control the discharge of fluid through said spout, a movable rod having a hook for holding said spout with its discharge end in an elevated position, and means connected with said valve for retaining said hook in a retracted and non-available position when the valve is open.
11. In a liquid dispensing can having a tilttable discharge spout leading from the lower portion thereof, and a valve to control the discharge of liquid through said spout, a device to retain said spout in an upright position comprising a movable part which, when in one position, will prevent said spout from being operatively engaged by said device, and a device to operate said valve and to retain said part in said position when said valve is open.
- In testimony whereof we have signed our names to this specification.
